CLEANING DEVICE

Frank Czpar, 4217 Swift St., San Diego, Calif.

Filed Jan. 17, 1958, Ser. No. 709,564

1 Claim. (Cl. 15—129)

My invention relates to a cleaning device, and has more specific reference to a portable cleaning implement which is particularly useful in washing automobiles.

In order to remove the dust and road grime from the painted surface of modern automobiles, it is necessary to flood the surface with water, and to scrub it with a soft material in order to dislodge the dirt which is then carried away by the water. The object being used to scrub the surface should not be rough otherwise scratches will appear in the surface of the finish. The material being used should also be sufficiently tough and tear-resistant, so that it will not rapidly go to pieces during the washing operation.

I have found that synthetic sponges, such as cellulose sponges, are ideal for washing automobiles in that they readily absorb water and become relatively soft, and yet are sufficiently tough that they will not disintegrate during a washing operation.

Also, in washing a car, it is essential to have sufficient water flooding the surface at the area being scrubbed, so that grit particles will be readily flooded away and will not tend to adhere to the scrubbing medium to thereby scratch the surface. Whereas, the volume of water flooding the surface must be sufficient to carry the dirt away, it is rather unpleasant to the operator to have too much water because it tends to splash on the operator and get his clothing wet.

The ideal manner for washing a car is to have a tough, relatively soft object, such as a cellulose sponge, with a constant supply of slow-running water being deposited on the surface adjacent the point being scrubbed. This is usually accomplished by holding a sponge in one hand and a water hose in the other. Whereas, such operation results in a satisfactorily cleaned car, it is awkward from the operator's standpoint.

I am aware that other devices have been produced and sold which attach to a water hose and supply water through the device being used for scrubbing the car. However, so far as is known by applicant, such devices are unsatisfactory, in that there are exposed metal parts which may result in damage to the surface. Also such devices depend for their scrubbing action on a high-velocity stream of water. This is not only wasteful of the water, but is unsatisfactory from the standpoint of the operator because it frequently splashes on and gets his clothing wet.

In some cases, in order to remove all of the grime and dirt resulting from driving on modern highways, it is necessary to first wash and scrub the car with water containing a detergent. So far as the applicant is aware, this has been accomplished up to now, solely by the means of dipping the scrubbing means in a bucket of detergent dissolved in water and scrubbing the car; then taking a hose to wash the removed or loosened dirt and detergent off of the finish.

With the foregoing discussion of the prior art in mind, it is one of the objects of my invention to provide a device for washing vehicles, which is soft enough to avoid in-

2

jury to the finish and has no exposed metal parts in a position to injure the surface while so washing it.

It is also a further object of my invention to provide a cleaning device capable of being attached to a hose or water supply which permits a relatively slow flow of water through the device on to the surface of the car while the car is being washed, thereby avoiding leaving dirt deposited on the surface, and also, avoiding excess of splashing as the water runs from the car.

10 Yet another object of my invention is to provide a cleaning device into which measured quantities of cleaning detergent may be disposed, which said detergent is slowly fed into the water flowing through the cleaning device, so that upon washing the car with a detergent, separate implements are not necessary.

These and other objects and advantages will become readily apparent to those skilled in the art, to which the invention applies from a reference to the following drawings and description relative thereto. In the drawings, 20 I have shown an example of one embodiment that my invention may assume. It should be understood, however, that the details hereinafter set forth, are by way of illustration only and not for purpose of limitation.

In the drawings:

25 Fig. 1 is a top plan view, partially in section, of one device embodying the principles of my invention;

Fig. 2 is a side elevation, partially in section, of the embodiment of my invention illustrated in Fig. 1;

30 Fig. 3 is a sectional view taken on line 3—3 of Fig. 2 of the inner tube only;

Fig. 4 is a detail view of a detergent tube partially revealed in Fig. 1.

35 Referring now in more detail to the drawings, I have provided a scrubbing pad, designated generally 10, formed as a rectangular block of a relatively soft, porous, tough material. Whereas it will be readily apparent that a great many other materials can be used, I prefer such material as synthetic cellulose sponge for the reason that it readily absorbs water and permits water to flow through the body thereof.

The rectangular pad 10 is formed with an aperture 11 extending longitudinally through the pad from one edge to the other. A collapsible conduit 12 is inserted through the aperture 11 and extends from edge 13 to edge 14.

45 A retainer plate 15 is formed with parallel slots 16 and 17 and performs the function of retaining one end of the conduit 12 in the assembly. The conduit 12 is disposed through the slot 16 outwardly beyond the surface 14, and reverse folded back through the slot 17.

50 A hole 18 is punched through the end of the conduit 12 and extends in axial alignment through both folds thereof. A rivet 20 is inserted therethrough to hold the two ends together.

Whereas a great many other embodiments may be 55 adopted for holding the conduit 12 in the assembly, the means which I have illustrated is simple and effective and not only holds the conduit 12 in place, but by reverse folding the end back inside of the body 10, any possible leakage of water takes place inside the body 10 and 60 assists in wetting the surface being scrubbed.

The other end of the conduit 12 is secured to a standard 65 hose fitting having a universal cap 22 secured to a body 23. The securement between the conduit 12 and the body 23 is by standard method, now well known to the water hose industry. A flange 24, preferably formed of rubber, is disposed over the hose connection body 23 and abuts against the universal coupling 22, thereby holding the assembly securely in place.

70 It will also be noted that the conduit 12 is formed with a plurality of apertures such as 25, preferably disposed along the lateral edge thereof. The size and spac-

ing of the apertures 25 control the dispersion and volume of water flowing through the cleaning device.

In the operation, the hose coupling 22 is screwed on the end of the water hose and water permitted to flow through the conduit 12 out through the apertures 25. This water rapidly soaks through the body 10 on to the surface of the bar being washed, so that it may be scrubbed and rinsed at the same time with a simple one-handed operation and without the encumbrance of awkward metal tubes or other devices.

I have also provided a means, in connection with my cleaning device, for adding measured quantities of detergent at controlled rates. The means comprises a tubular member 30 which as seen in Fig. 1 is inserted inside of the conduit 12. The tube 30 as shown in Fig. 4 has a plug 31 permanently affixed at one end and a removable stopper, such as 32 at the other end. The tube is provided with means for permitting the fluid contained inside to flow outwardly into the conduit 12. I have herein illustrated that means as a relatively small aperture 33 positioned adjacent the openable end of the tube 30.

Whereas, the detergent tube 30 can be formed of substantially any relatively rigid material, I prefer to form it of an aluminum tube because it is light in weight and sufficiently rigid to push inwardly into the conduit 12 even in its collapsed condition, as shown in Fig. 3. In the event that the tube 30 were collapsable, using the pad 10 and placing pressure thereon, would tend to squeeze the tube 30 closed and force the detergent, inside, into the water, resulting in uneven flows of the detergent.

I prefer one or more relatively small apertures at the stopper end of the tube which permits a relatively slow flow of the detergent contained in the tube out through the apertures into the water while washing the car. One reason for preferring the location of the apertures near the stoppered end is that the detergent tube 30 is inserted into the conduit 12 by pushing the plug 31 end in first. Water flowing into the cleaning device, flows through the coupling 22 and through the tube from right to left, as seen in Fig. 1, so that the detergent in flowing out of the detergent tube 30 mixes with the water and is carried the full length of the cleaning device. If the apertures were situated at the plug 31 end of the detergent tube, only the left hand end of the cleaning pad 10 would tend to have detergent.

Whereas I have illustrated my invention in what I conceive to be the most practical embodiment thereof, I do not mean to limit myself to the specific details of construction herein illustrated and described. It is readily apparent that a great many different materials, sizes and shapes can be used within the scope of my invention, the true scope of which is set forth in the appended claim.

I claim:

10 A cleaning device comprising: a scrubbing body formed of a relatively soft, porous, water absorbent material and having an aperture extending axially therethrough; a flexible conduit member disposed in said aperture and extending beyond the peripheral edges of said body, said conduit being formed with a plurality of holes for communication between the interior of said conduit and said scrubbing body; means for sealing one end of said conduit and preventing withdrawal of said end interiorly of said body, said means comprising a flanged member having a larger diameter than said aperture and being formed with spaced slots, said flexible conduit having one end extending outwardly through one of said slots and folded back to extend inwardly through the other of said slots; hose coupling means secured to the other end of said conduit and being provided with a flanged member larger than said aperture whereby said conduit is prevented from being withdrawn inwardly into said body; detergent supply means removably disposed inside said conduit, said detergent supply means comprising a tubular member adapted to contain liquid detergent and being formed with a relatively small discharge aperture adjacent one end thereof, said end being adapted for discharge adjacent said hose coupling end of said conduit.
